FIG. 4

FIG. 5

BY

Herbert J. Cleary

E. G. Charles

ATTORNEY.

INVENTOR.

UNITED STATES PATENT OFFICE.

HERBERT J. CLEARY, OF TOPEKA, KANSAS.

SULKY PLOW.

Application filed November 3, 1926. Serial No. 146,034.

My invention relates to improvements in sulky plows.

The object of my invention is to provide a simple carrying and conveying means for a ground breaking plow.

A further object of my invention is to provide a sulky plow having large wheels so that the ordinary resistance at the traction point will be from that of a smaller wheel.

10 A still further object of my invention is to provide a carrying means having the plow pivotally connected thereto by parallel bars.

A still further object of my invention is to provide a hitching means for the plow to the frame of the sulky that the point of the plow may be inclined downward so that the cutting and turning of the ground tends to wear on the top of the plowshare rather than the under side by which means a better cutting 20 edge may be retained, and furthermore the weight of the plow in its operation is imposed on the large wheels, the tendency of which is to run more easily over soft or uneven surfaces.

25 A still further object of my invention is to provide a turning means for the guide wheel automatically by the turning of the power conveying means.

A still further object of my invention is to 30 provide lever actuating means for the vertical movement of the frame of the guide and land wheels, and a direct hitching means of the sliding members.

These and other objects will hereinafter be 35 more fully explained.

Referring to the drawings:

Fig. 1 is a side elevation of the mechanism.

Fig. 2 is an enlarged transverse view in detail, looking toward the front.

40 Fig. 3 is a plan view.

Fig. 4 is an enlarged elevation of the land wheel adjusting means, the lever position modified by extending rearward.

Fig. 5 is a plan view of Fig. 4.

45 The mechanism herein disclosed consists of a rectangular frame 1 having parallel bars 2 intermediately and longitudinally disposed. The said bars function as carrying means for the plow hereinafter described. The frame 50 is rigidly braced by rods 3 diagonally positioned as shown in Fig. 3. The front end of the frame is semi-circular in form as shown at A for the concentric position of a guide wheel 4 in the curvature.

55 The furrow side of the sulky is carried by a large wheel 5 trunnioned on a spindle 6

which is rigidly attached to its respective side of the frame. On the opposite side of the frame is a wheel 7 trunnioned on a spindle 8, the said spindle being integral with a 60 sliding member 9 having a plurality of perforations 10 centrally and longitudinally distributed thereon. The said sliding member engages in a member 11 which is of a channel form having returned edges to lap over the edges of the said sliding member. In the upper end of member 11 is an aperture 12 adapted to register with a chosen aperture in the sliding member. As a means for raising and lowering the frame I have positioned a 70 standard 14 rigidly connected thereto, the upper end thereof as a pivoted fulcrum point for a lever 15, the short end of which is pivotally connected to the sliding member 9 as at B.

75 The guide wheel 4 is trunnioned in a bifurcated upright member 16 having a shank on the upper end thereof trunnioned in a bearing 17, the said bearing being integral with a laterally extending member 18 which is rigidly attached to the frame and functions as a draft connecting means for the mechanism to a tractor or other means of motive power. On the under side of the frame is a member 19 which is bifurcated, the legs running in opposite directions following the curvature of the frame and rigidly attached thereto, the forwardly extending ends of the members have apertures in vertical alignment to receive a pin 20 revolvably but rigidly engaging through a 80 block 21 positioned between members 18 and 19. On the outer end of the block is pivotally connected a clevis 22, the said clevis having a transversely positioned bar 23 with a 85 plurality of apertures 24 longitudinally spaced thereon, the object of which is to vary the draft alignment of the frame, and two or more of the apertures may be engaged by the hitching means to the motive power. 90

95 Rigidly attached to the upper end of the pin 20 is a sprocket wheel 25 and slidably engaging on the shank of the guide wheel is a sprocket 26, the said wheel being keyed to the shaft in such a way that the said shaft is free to slide therethrough as the frame is raised and lowered, this being the means to keep in proper alignment the two said 105 sprocket wheels so that a chain 27 will engage thereon. It is now readily seen that by turning the clevis to the right or left as indicated by dotted lines in Fig. 3 the guide 110

wheel will be turned simultaneously and equal with the turn of the clevis and block attached thereto.

As a means for raising and lowering of the front end of the frame, I have provided a standard 28 rigidly attached to member 18. Pivotally connected to the top end thereof is a lever 29, the said lever engaging in the forks of an upright member 30 having a plurality of apertures longitudinally spaced thereon as shown in Fig. 1. The said lever 29 has an elongated aperture centrally positioned therein to register with the apertures in the fork and to engage rigidly therewith by means of a pin 31, the said means being a rigid support for the frame relative to the guide wheel.

As a conveying and raising means for the plow 32, I have provided parallel bars 33 pivotally connected to the bars 2, the opposite end of said parallel bars being pivotally connected to the beam of the plow as at C. As a means for raising and lowering the plow I have provided a toggle joint 34, one member being pivotally connected to the beam of the plow, and the other rigidly connected to a spindle 35 rotatably mounted in a notched sector 36. Rigidly connected to the said spindle is a lever 37 having a pawl 38 slidably positioned thereon, the lower end of which will engage with the notches of the sector as stationary positioning means for the plow.

In Fig. 1 is shown the plow positioned so that the share is on a level with the bottom of the furrow wheel. When it is desired to plow to a greater depth, the toggle may be thrown to a straight alignment lowering the plow below the traction point of said wheel until one round has been made on the land which it is plowing. The second round the plow will be raised to the level of the former furrow, at which time it will continue to plow to the depth of the first furrow. Shallow plowing may be obtained in a like manner but by reversing the movement, that is to say, raising the plow above the level of the traction point of the furrow wheel, and readjusting for the second round to the level of said wheel the depth of the first furrow.

The plow may be raised until the beam 39 is on a level or above the bars 2. Note that the parallel bars 33 are in pairs carrying both ends of the plow beam which is positioned therebetween, the beam and bars will pass between bars 2 without obstruction.

The pivot point of the parallel bars 33 connecting with the plow are placed on the under side of the beam so that the said beam will be supported in an upright position between the bars 33 which is a vertical positioning means for the plow while in operation or disengaged.

The sulky mechanism disclosed may be employed for drawing listers, or other forms of ground breaking devices, but the drawings show it in connection with an ordinary side plow. The frame may be increased in width so that other bars similar to bars 2 may be placed thereon forming what is commonly known as gang plows. In such event the said frame 1 may be varied in its shape so that the plows will immediately follow each other without obstructing the turn of the ground.

Such other modifications may be employed as lie within the scope of the appended claims.

Having thus described my invention, what I claim as new and desire to secure by Letter Patent is:—

1. In a sulky plow, the combination of a frame mounted on wheels, parallel bars longitudinally and intermediately positioned in the frame, of diagonal bracing between the parallel bars and the sides of the frame, of a plow with its beam centrally positioned relative to the bars, of bars pivoted to the first of said bars and being rearwardly inclined and pivotally connected to the plow beam, and means to raise the plow so that the beam will pass between the first of said bars.

2. In a sulky plow, the combination of a frame carried on wheels of large diameter to elevate the frame, of a pair of bars spaced apart and carried by the frame, of parallel bars pivotally engaging the inside of first said bars, a plow and a beam therefor, pivotal connecting means on the under side of the beam, one at the rear and the other near the forward end of the beam to which the last said bars pivotally engage so that the beam and plow is vertically guided by the last of said bars, a toggle joint pivotally connected to the top edge of the beam adjacent the rear end and means to operate the same so that the bars, beam, and toggle joint will position between the first said bars when the plow is raised, all as and for the purpose described.

HERBERT J. CLEARY.
